United States Patent Office

Des. 183,083
Patented June 24, 1958

183,083

TRANSFORMER

Joseph L. Bonanno, South Orange, N. J., assignor to The Lionel Corporation, New York, N. Y., a corporation of New York

Application May 13, 1957, Serial No. 46,123

Term of patent 14 years

(Cl. D26—15)

Fig. 1 is a perspective view of a transformer showing my new design;

Fig. 2 is a top plan view;

Fig. 3 is a side elevational view, the opposite side having substantially the same appearance; and

Figure 4 is a front elevational view thereof, the rear having substantially the same appearance.

I claim:

The ornamental design for a transformer, as shown and described.
